ELECTRICAL CONNECTOR

Julian Rogoff, New York, N. Y.

Application February 24, 1940, Serial No. 320,669

2 Claims. (Cl. 24—243)

This invention relates to an electrical connector, and more particularly to a split-bolt having a resilient separable element for applying spring pressure to the elements clamped by the connector.

I have found that in split-bolts of the foregoing type, the conductors being of softer material than the connectors, sometimes "creep" under the clamping pressures thus loosening the connections and reducing the electrical efficiency of the connector. This is especially true of aluminum conductors, and where the elements or wires are subject to vibration.

Accordingly, a primary object of my invention consists in providing a resilient element in the assembly which will keep the elements under continual pressure and in good contact with each other.

Other objects are to provide a resilient element, that is bowed to secure continuous resiliency; that is in embracing relation to the bolt to prevent rotation and displacement thereon; and which may include portions disposed between the shank portion of said bolt.

I accomplish these and other objects and obtain my new results as will be apparent from the device described in the following specification, particularly pointed out in the attached claims, and illustrated in the accompanying drawing, in which:

Fig. 1 is a front view of the bolt, with a portion thereof in section.

Fig. 2 is a sectional view of the bolt in the plane indicated by the lines 2—2 of Fig. 1, and in the directions indicated by the arrows.

Fig. 3 is a plan view of the resilient element, in position about the shanks of the split-bolt.

Fig. 4 is a plan sectional view of the bolt, taken in the plane indicated by the lines 4—4 of Fig. 1, and in the directions indicated by the arrows.

Fig. 5 is a side view of the bolt.

Fig. 6 is a side view of the washer.

Fig. 7 is a front view of the same.

Referring more particularly to the drawing, reference numeral 10 indicates the bolt, having a head 11 provided with flat sides 12 for engagement with a wrench or other tool. Integrally extending from the head 11 are a pair of spaced apart externally threaded shanks 13 and 14, terminating in an engaging nut 15 and washer 16 mounted thereon.

The washer 16 is provided with an element engaging surface 17, of sufficient length to avoid scoring the elements 18 contained between the shanks 13 and 14 of the bolt. At each end of

the engaging surface 17, are integrally mounted sections 19 against which the upper surface 20 of the nut rotates. The washer is of a width enabling it to be spaced freely between the shanks 5 of the bolt, and extends slightly below the lower surface 21 of the nut so that sections 22 may be swaged therefrom to capture the nut 15 between the sections 22 and sections 19.

Thus, as the nut 15 threadly rotates on the 10 threads of the shanks, the washer is moved linearly in the space between the shanks of the bolt. Since the washer engages the element 18, it is of substantially non-yielding material.

The resilient element 25 is provided with cut-outs 26 and 27 to accommodate the shanks 13 and 14 of the bolt, and preferably contain portions 28 and 29, which are bowed, as shown in Fig. 1, which extend from the body of the resilient element, from opposite sides of the cut-outs, towards each other and have a width and length sufficient to allow them to be disposed in the space between the shank portions, and to be depressed under pressure, without engaging each other at their free ends.

25 The resilient element may be constructed so as to embrace the bolt adjacent to its head 11, or may obviously be placed on said bolt, after the elements have been inserted thereon, so that it will contact the conductor element 18, and the engaging surface 17, of the washer 16. In the latter instance the cut-outs 26 and 27 may approach in outline the circumference formed by the shanks 13 and 14. Additional resiliency is obtained.

30 A further spacing element 30 may be used to space the conductor elements from each other, especially where they possess different electrochemical characteristics.

35 The resilient element 25 may be provided with the ends 31 bowed in the directions taken by the portions spaced between the shanks, as shown in Fig. 1. The element is considerably improved thereby.

40 I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming 45 within the scope of the appended claims, and by means of which, objects of my invention are attained and new results accomplished, as it is obvious that the particular embodiments herein

shown and described are only some of the many that can be employed to attain these objects and accomplish these results.

What I claim and desire to secure by Letters Patent, is as follows:

1. A wire connector comprising a bolt-head having spaced apart shank portions screw-threaded at their outer faces and V-shaped at their junction thereof, a nut and follower assembly mounted on said spaced apart shank portions of said bolt, the follower of said assembly being entirely of substantially non-yielding construction, said nut being arranged to move said follower longitudinally of said bolt in a straight-line non-rotatable manner as the nut is screwed longitudinally of the bolt so as to clamp one or more elements between said follower and a part of said bolt, and a resilient washer interposed between the wire elements and the bolt-head and provided with an aperture shaped to engage the side walls of said bolt-head, and two inwardly extending bowed portions positioned between the spaced apart shank portions, whereby tightening the nut and clamping the wire elements will 25

cause the inwardly extending bowed portions to be compressed.

2. A wire connector comprising a bolt-head with two flat parallel sides and having spaced apart shank portions screwthreaded at their outer faces and V-shaped at their junction thereof, a nut and follower assembly mounted on said spaced apart shank portions of said bolt, the follower of said assembly being entirely of substantially non-yielding construction, said nut being arranged to move said follower longitudinally of said bolt in a straight-line non-rotatable manner as the nut is screwed longitudinally of the bolt so as to clamp one or more elements between said follower and a part of said bolt, and a resilient washer interposed between the wire elements and the bolt-head and provided with an aperture having two parallel edges which engage the two flat sides of the bolt head, and two inwardly extending bowed portions positioned between the spaced apart shank portions, whereby tightening the nut and clamping the wire elements will cause the inwardly extending bowed portions to be compressed.

JULIAN ROGOFF.
